UNITED STATES PATENT OFFICE.

FRANK O. WOODLAND, OF WORCESTER, MASSACHUSETTS.

LABELING-MACHINE.

No. 818,506.

Specification of Letters Patent.

Patented April 24, 1906.

Application filed June 27, 1902. Serial No. 113,417.

To all whom it may concern:

Be it known that I, FRANK O. WOODLAND, a citizen of the United States, residing at Worcester, in the county of Worcester and State of Massachusetts, have invented a new and useful Improved Labeling-Machine, of which the following, together with the accompanying drawings, is a specification sufficiently full, clear, and exact to enable persons skilled in the art to which this invention appertains to make and use the same.

The object of my present invention is to provide a labeling-machine of efficient capacity, simple in construction, and convenient for rapid operation; and my invention consists in mechanism embodying the special features of improvement and the combined organizations set forth and explained in the following detailed description and particularly defined in the summary.

In the accompanying drawings, Figure 1 represents a side view of a labeling-machine embodying the features of my invention. Fig. 2 is a front elevation view. Fig. 3 is a front view of the wiping-on mechanism. Fig. 4 represents a plan view of the carrier, picker-arms, and wiping-on devices. Fig. 5 is a sectional view showing an arrangement of wiper-resistance followers. Fig. 6 represents a top plan view of the machine with the carrier at its rearward position. Fig. 7 is a horizontal sectional view below the paste-box, label-holder, and wiper. Figs. 8 and 9 illustrate the structure and operation of the yielding roller grip-finger for staying the label to the bottle. Fig. 10 is a detailed bottom view of the roller grip-finger drawn to somewhat larger scale. Fig. 11 is a horizontal section detail of a frictional grip device for the label-holder stand. Fig. 12 shows in elevation and plan view one of my adjustable label-holder pins. Fig. 13 is a transverse sectional view showing the label-supply holder and its sliding bed and illustrating a modification in its readjusting means, and Fig. 14 illustrates the label-holder as made with the jaw device attached to the sliding bed-piece and Fig. 15 is a detail view of the tumbler-engaging devices upon the bottom of the paste-box.

Referring to the drawings, A denotes the supporting-frame; B, the stationary upright guide-rods.

C indicates the wiper-stands fixed upon the frame and having the wipers D secured to the upper ends thereof, said wipers prefer-

ably consisting of rectangular plates of vulcanized rubber or other suitable moderately flexible material having sufficient resilience to give a yielding pressure and to return to their normal horizontal position after the wiping-on action. The outer edges of the wipers are rigidly secured to the stands C, from which they project toward each other, and with their inner edges free for flexure at either side of the passway.

E indicate arms or resistance-levers provided with follower fingers or rollers 3, that underlie and movably uphold the wiper-flaps D, as more fully hereinafter explained.

F indicates the reservoir or box for containing the glue, paste, or adhesive material employed for sticking the labels, said paste-box having the paste-delivering roller F' rotatably mounted therein and a surface scraper 75 f for gaging the film of paste thereon in well-known manner.

G indicates the transferring-carrier, H the label-holder for containing the feed-supply of labels L, and I the picker-fingers supported upon the carrier by upright pivots J and having at their fore ends the pasting-pickers P, which latter are firmly, but detachably secured thereto and are interchangeable in various sizes and shapes for 85 different sizes and forms of labels. To facilitate this interchange and for securing the pickers P to the fingers I, the pickers of the several different forms or sizes are each provided with a similar-shaped slotted ear or 90 projection P', each being adapted to seat in similar manner and position upon the end portion of the finger, where the picker is firmly but detachably secured by a clamp-bolt or cap-screw p, arranged through the 95 slotted ear portion and threaded into the metal of the finger, as best shown in Figs. 1, 2, 3, and 4. By merely loosening the cap-screws the picker is freed so that it can be taken off and quickly exchanged or replaced 100 on the finger when desired. The fingers I are drawn toward each other by a spring i against arresting-lugs i². The carrier G is supported at opposite sides of the frame by dual parallel swinging arms K and K', having their upper ends pivoted to the carrier and their lower parts or ends fulcrumed on the frames, as at K². Said arms are adapted to swing the carrier backward and forward for moving the pickers from a position above 105 the wipers to the label-holder, and vice versa, said carrier moving in the line of a crowning

110

arch, the radius of which corresponds to the swing of the arms, while the carrier-plate fingers and pasting-pickers are maintained in a relation of horizontality and the pickers 5 pass in contact with the paste-delivering roller F', which is elevated by suitable means during the rearward movement of the carrier.

As a feature of my invention the label-holder H is arranged to have an edgewise 10 backward-and-forward action on a line convergent to the line of motion of the carrier and picker devices, so that the differential movement of these parts as they travel backward together brings the pasting-pickers 15 down upon the pile of labels for picking a label therefrom, which label is lifted for transfer to the place for wiping on at the forward movement of the carrier, while the label-holder returns to primal position. The label-holder preferably comprises a supporting-stand 8 with a stem 9 and steady-pins 10, and a detachable top-plate 7, whereon the labels L are stacked, with upright pins 11 at the edges of the pile for steadyng the pile on 20 the plate and retaining the labels in uniform order.

In the present instance the label-holder standard 9 and its steady-pins 10 are mounted in a reciprocating bearer or bed H', that 25 slides on horizontal guide-rods 12, supported on a rearwardly-projecting part a^2 of the frame. The label-holder or its sliding bed has connected therewith an engaging device or jaw 13, and the carrier G is provided with 30 a detent or roller-stud 14, that coacts with said jaw as the carrier swings backward, thereby causing a coincident rearward movement of the label-holder and the picker devices, the one moving on a curve, the other 35 on a line that intersects said curve at a certain rearward position, so that the pickers fall upon the labels supported upon the holder gradually but with certain precision. The engaging devices or jaw 13 is best provided 40 with a front member, by which forward movement of the label-holder, together with the carrier, is effected. This avoids the necessity of 45 a return-spring for label-holder, which might be otherwise employed for returning it to primary position.

The stem or standard 9 of the label-holder is vertically movable in the bed H', and a friction grip device 15 is provided therein for retaining the standard and label-holder at 50 elevated position, except when the grip-resistance is overcome by a superior force. Beneath the standard upon the frame A there is an inclined cam-surface 16, against which the standard 9 runs and which causes the label-holder, if depressed, to assume its normal 55 level or elevation when at forward position. When moved rearward, the standard leaves the cam-surface 16, and depression of the label-holder can occur when the pickers press 60 upon the pile of labels L with sufficient force

to slide the stem in the friction-grip 15. This construction enables the picker mechanism to act upon the pile of labels L uniformly when taking a label therefrom, whether there are few or many labels in the pile. The friction device 15 may comprise a friction-piece 17 or spring 18 and a tension-adjusting screw 19, as illustrated in Fig. 11.

Frequently in practice labels of different lots intended for the same size will be found to vary slightly in cut dimensions, and to adapt the label-holder for properly accommodating such variations I construct some of the retaining-pins, as those for one side and one end, as indicated in Fig. 12, with a 70 support or offset foot 21, consisting of an eye and projecting arm having the upright pin rigidly fixed upon the end of said arm and secure the same to the holder-plate by a fastener stud or screw 22, fitting the eye as an 80 axis, and attaching the arm and pin firmly to the label-holder plate, said axis-stud being disposed at a position laterally out of alignment with the bearing line or axis of the pin, so that the pin can be adjusted outward or 85 inward by a swinging movement or slight rotation of the foot about the axis of its attaching-stud. This simple means of adjustment is of considerable convenience and utility, and is comparatively inexpensive for 90 construction.

When desired, the label-holder is provided with yielding or spring finger devices 20 and independent of the label-retaining pins to facilitate the separation and single delivery of 100 the labels. Said finger device preferably consists of a wire coil fixed on the plate 7, and having a free swinging arm or resilient portion that latches slightly at its end over the edge of the pile of labels, but not so strong as 105 to prevent the top label being raised therefrom.

M indicates the pusher-head that slides upon the guide-rods B and carries the push-brace 23, by which the bottle is pressed down 110 the passway between the wipers. As a feature of my invention said cross-head is provided with outwardly-inclined cam projections 25, and the picker-fingers I are provided each with an extension or upper projecting member I', that extends beneath said cam-surface when the pickers are at forward position. The first impulse of downward movement of the bottle-pusher head causes, by the cam-surfaces running against the extension members I', a positive lateral movement of the picker-fingers I, which draws the pasters sidewise off the ends of the label l as the bottle and label come into conjunction with the ends of the wipers. As the cams 25 are freed from the fingers the latter are drawn 120 inward against their gage-stops i^2 by the contractile spring i, which connects the picker-fingers.

For imparting a yielding resistance and up- 130

holding the wiper-pads against the label as the bottle is forced through the passway I provide a pair of levers E, fulcrumed at their lower ends, preferably upon the wiper-stands 5 C, as at e, and each having at the top end a bar, finger, or roller 3, that extends along the under surface of the wiper D—one at each side of the passway—and approximately parallel with each other, their normal idle position 10 being near the free ends of the wipers. These arms or levers are crossed so that their top ends 3 can swing oppositely outward toward the stands C. The two arms are connected by a pivotally-attached bar E, that causes 15 them to move in unison, and stop-lugs 4 are provided to arrest the inward swing of the levers when the followers are at their normal position. A spring or springs connected with the levers imparts yielding resistance to their 20 action. Preferably two springs 5 and 6 are employed—one of moderate tension connected to exert its force at the commencement of the follower action and the other connected by a lost-motion loop or eye in a manner to exert 25 its force after the follower has moved back for a given distance, it then being brought into action to augment the resistance of the followers as the wipers press the sides of the bottle.

30 The connecting-bar E' may, when desired, be provided with a guard-tongue 27 (see Fig. 3) to ward off the end of the bottle from striking the levers, or in other instances said guard-tongue may be omitted, as in Fig. 2.

35 The function of the arms E and followers 3 is to cause the flexible wipers to hug the label to the sides of the bottle in a more perfect and efficient manner than would otherwise be effected and to vary the direction of pressure as the rotundity of the bottle changes its 40 relation or location in passing the stationarily-supported wipers.

A depending end gage 29, adjustably secured to a rearwardly-projecting arm of the 45 head-piece B', serves for gaging the position of the bottle when placed for receiving the label. The bottle is indicated by dotted lines x in Figs. 1, 2, 3, and 6.

For the central retention of the label 50 against the bottle I provide an under jaw appliance or roller grip device carried by a yieldable supporter and adapted to permit withdrawal of the bottle without first mechanically releasing or throwing off the grip. 55 As at present constructed said means is best shown in Figs. 8, 9, and 10. A roller 33, of vulcanized rubber or suitable elastic material, is mounted to rotate freely on a transverse axis-pin 34 in a vertically-swinging arm 35. 60 Said arm is hinged or fulcrumed on a support 37, attached to the lower part of the sleeve m of the pusher-head M to have upward and downward action therewith. A spring 36 is secured to the arm and acts against the support-piece 37 to normally swing the arm and

roller upward, as shown in Fig. 9. The arm 35 is provided with a laterally-projecting finger 38, that comes into contact with one of the wiper-followers 3 when the pusher-head approaches its extreme elevated position, 70 thereby arresting the arm and causing the roller-grip to assume the position shown in Fig. 8 for giving ample space above the roller and below the bottle position for the presentation of the label l by the pasting-pickers. 75 Downward movement of the pusher-head M relieves the finger from its restraining contact, and the spring 36 acts to press the roll 33, with the label l, strongly against the bottle for preventing displacement of the labels 80 while acted upon by the wipers. This grip-roll by its free rotation permits of the bottle being easily drawn out endwise after it has passed the wipers and without disturbing or injuring the recently-attached label. 85

An actuating-lever 48, fulcrumed at 49, has one arm connected by a link-bar 44 for moving the carrier-supporting arms K, while its other arm is connected by a suitable link-bar 45 for moving the vertically - reciprocating 90 pusher-head M and devices that are connected therewith. The actuating-lever 48 is joined by a connection-rod 50 with one arm of a rocker-lever 51, fulcrumed on the base A' of the frame-standard a, and the other 95 arm of said rocker-lever extends upward outside the base and is provided with a stud or roll 52, that engages in the groove of a cam-wheel 53, mounted on a shaft or axis 54, supported in suitable bearings a' on the frame-standard base. A drive wheel or pulley 55 is mounted on said shaft, and an automatic stop-clutch 56 is provided between the pulley and cam, whereby the cam can be clutched to rotate with the pulley or released to remain inactive. An angle-lever 57, pivoted on the base at 58, has one arm fitted for putting the clutch into engagement and throwing off the same, while its other arm is fitted as a treadle 59 to be depressed by the foot of the operator. A suitable spring is employed in connection with the starting-lever for pressing up the treadle and swinging the lever into position for throwing off the clutch and stopping the rotation of the cam. The 115 clutch may be of any suitable construction or may consist of a longitudinally-sliding spring-pressed dog fitted in the hub of the cam and adapted to lock into a hold or recess in the side of the pulley-hub, said dog having a projecting lug that runs onto the inclined side of the starting-lever for retraction of the dog in opposition to its spring and to automatically release the cam from the pulley. The rotation of the cam rocks the lever 51 120 and by the rod 50 depresses and raises the actuating-lever 48, which works the label feeding and affixing mechanisms.

The tumbler-cam 60 for elevating the paste-box F is pivoted on the frame and connected 130

to the lever 48 by a link 61, an escape member 62 being provided on the paste-box, so that the cam acts to lift the paste-box when it swings in one direction, but passes without lifting said paste-box when moving in the other direction. The escape member preferably consists of a laterally-swinging arm 62, (see Fig. 15,) pivoted, as at 66, to the bottom of the paste-box F and provided with a lug, roll, or detent 65 for engagement with the tumbler-cam 60. A spring 64 is provided for retracting or swinging said arm to its normal position of alinement with the path of the cam, at which position the end of the arm rests against a stop-lug 63, fixed on the bottom of the box, but said spring permits a yielding action of said arm laterally. When the tumbler-cam 60 moves rearward, its face passes beneath the face of the roll 65, and elevation of the paste-box is thereby effected; but with the reverse movement of the tumbler-cam the yielding of the spring 64 as the cam strikes the detent or roll 65 allows the arm to swing laterally, thereby throwing said roll out of alinement, so that the cam passes it at one side instead of beneath it, and no lifting effect is exerted on the paste-box during the retractive movement of said cam.

The operation of the machine is as follows: Assuming that the pulley 55 is running and that a label l has been presented above the wipers D by the pasting-pickers P, the attendant then introduces a bottle beneath the push-brace 23, as indicated at x, Figs. 1 and 2, and depresses the treadle 59. This swings the end of the lever 57 outward from clutch 56, the dog of which is released and springs into engagement with the pulley 55, thereby starting the cam 53, which in turn effects movement of the rocker-lever 51 and rod 50, drawing down the actuator-lever 48, and thereby simultaneously depressing the pusher-head M and swinging back the carrier G with the picker devices. By the movement of the pusher-head the inclines 25, coacting with the extension members I' on the picker-fingers I, positively spreads the pasting-pickers apart, and at the same time the retreat of the projection 38 from the wiper-follower 3 permits the roller 33 to grip the label against the bottle for retaining it central, while the bottle and label are pushed down between the wipers and followers 3, which latter act, with the resistance of their spring or springs 5 and 6, to hug the flexible stationary wipers D against the label and follow it around the rotund surface of the bottle, wiping it on in a very efficient and perfect manner. When the bottle has passed the wipers, it can be readily withdrawn, as the rotation of the grip-roller permits its exit without injury to the label and without requiring an opening action for the bottle-holding mechanism. While the above wiping-on action is going on

65 the carrier G moves rearward, and the paste-

box F is bodily lifted by the cam 60, causing the paste-delivering roller F' to supply a coating of paste or glue to the pasting-pickers as they pass toward the label-holder H. When the pasting-pickers arrive at the proper position, the roll or lug 14 on the carrier G engages the jaw 13, and the label-holder bed is thereby caused to slide rearward on its guides 12, and the pasting-pickers P are brought into conjunction with the pile of labels l on the holder-plate by the differential lines of rearward movement traveled by the label-holder and the carrier. The label-holder by pressure of the pickers becomes depressed in the required degree to accommodate the level or top of the pile of labels to the picker-level when at its rearmost limit, (see dotted lines R, Fig. 1,) the label-holder standard sliding in the bed against the adjusted friction of the frictional device 15. By the forward movement of the carrier the label-holder bed and label-holder are returned to their primal position, and the holder-stand and plate is raised to its normal level by the end of its standard running onto the cam or incline. The top label adheres to the pasting-pickers and is transferred to a position above the wipers ready for affixment to the next bottle in order by a repetition of the operation.

If preferred, a lifting-spring 26 may be employed in lieu of the frictional device 15 and incline 16 for controlling or readjusting the level of the label-supply holder as it returns to primary position, and said spring can be arranged as illustrated in Fig. 13 or in other suitable manner. One or two springs 26 connect with an arm 24, attached to the stem 9 and to the bed-piece H', and a stop-pin 42 is fixed in the stem to arrest the parts at normal position of readjusted level.

Having set forth and explained the nature of the invention and described one preferred embodiment of the same and the manner of its operation without attempting to enumerate all of the forms in which it may be made or modified by mere skill in the art without departing from the principles and scope of the invention, I declare that what I claim, and desire to secure by Letters Patent, is—

1. A labeling-machine comprising a movable carrier, means for pasting and picking up a label mounted on said carrier, means for reciprocating said carrier in an arched line of movement, a paste-box having paste-delivering means, elevating devices that move the paste-box toward the path of the pasting-pickers, a label-holder, a reciprocating label-holder support movable in a general direction with said carrier, but on a line differential to that of the carrier movement, and means for effecting uniform rate of movement for the pickers and label-holder as they converge and recede.

2. A labeling-machine, comprising, in com-

combination with wiping-on devices and a pusher mechanism; a transferring-carrier, dual parallel-swinging supports for said carrier, a pair of picker-fingers supported by vertical pivots on said carrier, pasting-pickers detachably secured to said fingers, a paste-receptacle and paste-distributing means, an edgewise-movable label-holder, means for guiding the label-holder, means for moving said carrier and pickers over the paste-distributing means, and to a position rearward of the normal position of said label-holder while the pickers act at coincident relation to the labels, and to effect synchronous convergent terminal movements of the same, for the purpose set forth.

3. A labeling-machine comprising a carrier mounted on upwardly-projecting parallel swinging supports, a pair of laterally-swinging arms pivoted on said carrier, a contractile spring and stops for said arms, pasting-pickers attached to said arms, a paste-box and paste-delivering roller, means for moving said paste-box to bring the roller into contact with the pasting-pickers, a label-holder having means for retaining a pile of labels thereon, a rearwardly and forwardly movable label-holder bed, guides therefor, a label-holder standard yieldably sustained in said bed, means for effecting a movement of said label-holder and its bed in unison with the movement of the pasting-pickers, and means for readjusting the level of the label-holder in relation to its bed as it returns to primary position.

4. A labeling-machine, comprising an oscillatory carrier carrying means for pasting and picking up a label, a label-supply holder, a carrier-supporting means that maintains the plane of the carrier and picking-up devices relatively parallel to the plane of the label-holder during the oscillatory movement, a paste-receptacle having paste-delivering roll, means for moving said carrier to pass the pasting-pickers in contact with the paste-delivering roll, and into alignment with the label-supply holder, and means for reciprocating the label-supply holder with the carrier, at each movement of the carrier, and means for returning the carrier to forward position with the label out of contact with the paste-delivering roll.

5. In a labeling-machine, in combination with the transferring-carrier and pasting-pickers carried thereon, a label-holder bed, backwardly and forwardly movable on a line differentially approaching that of said carrier, a label-holder supported and vertically adjustable in said bed, a friction grip device for normally sustaining the adjustment thereof, an automatically-engaging means for effecting movement of the label-holder bed and holder with the rear portion of the carrier movement, and a cam or incline that

readjusts the label-holder in its bed as it returns to primary position.

6. In a labeling-machine, and in combination, a label-carrier having oscillative movement, picker-arms pivotally mounted on said carrier, pasting-pickers attached to said arms, means for supplying paste to said pickers, means for delivering a label to said pickers, label-wiping devices, and a reciprocating pusher having means for passing the bottle between the wipers, said picker-arms and said pusher being provided with coacting members whereby a positive outward swing or lateral movement is imparted to said picker-arms and paster-pickers by the prime downward action of said pusher.

7. In a labeling-machine provided with a label-transferring carrier, wiper devices, and a reciprocating bottle-push mechanism, the laterally-swinging picker-arms pivotally mounted on said carrier and having the pasting-pickers supported thereon, said picker-arms respectively provided with extension members, in combination, with the bottle-push head having inclined cam projections thereon that act against said extension members for laterally spreading the picker-arms.

8. In a labeling-machine, the combination, of a flexible wiper, and a resistance-follower acting against the back or reverse surface of said wiper with a yieldable pressure, and movable along the wiper-surface.

9. In a labeling-machine, a label-wiping mechanism comprising a pair of stationary wiper-stands, oppositely-disposed wipers of moderately-flexible material respectively fixed to said stands, laterally-movable followers upholding the free portions of said wipers and carried by laterally-swinging arms, and a spring, or springs, connected with said arms for pressing the wiper-followers toward their normal or primary position with a yielding resistance.

10. The combination, with the flexible resilient rectangular wipers, supports for one edge thereof, their opposite edges free and projecting into the passway; of separate movable wiper-upholding followers adapted to press said wipers toward the bottle and to retreat with a yielding resistance, by lateral and downward swing movement toward the wiper-supports, as the bottle goes through the passway between the wipers.

11. In a labeling-machine, in combination, a pair of oppositely-disposed flexible flap-wipers, means for the stationary support of the outer edges of said wipers, a pair of parallel roller-followers rolling against the under surface of the wipers toward and from their flexible ends, means for supporting said follower-rollers to uphold the working portion of the wiper-flap, and means for imparting a yielding resistance to outward movement of said followers.

12. In a labeling-machine, in combination with means for pasting and delivering the labels, and means for passing a bottle through the wipers; the stationary wiper-stands, flexible wiper-flaps secured at one edge to said stands, crossed swinging arms pivoted at the foot thereof and provided at their tops with parallel bars or rollers that move along the under surface of the wipers, springs that force said arms inward, a pivotally-attached cross-bar connecting said arms, and a guard-tongue formed on said bar and projecting in front of the arms, for the purpose set forth. 70
13. In combination with means for pasting and presenting a label; of the wiper-stands, inwardly-projecting flexible resilient wipers fixed on said stands, resistance-followers acting beneath and against said wipers, follower-levers oppositely fulcrumed at the base of said stands and swinging said followers laterally toward and from each other, means for insuring uniform movement of the followers, a spring, or springs, connecting the levers, stops for limiting their approach, and means for pushing a bottle between the pair of wipers and followers. 75
14. In a labeling-machine, a pair of pasting-pickers, a movable carrier therefor with laterally-yieldable supports for said pickers, a pair of wipers, and a label-center stay comprising a yieldable grip device in combination with a reciprocating pusher-head, and means controlled by the pusher-head for simultaneously spreading said pickers laterally; advancing the bottle to the label and wipers, and raising said grip device into holding position against the label, by the movement of said pusher-head. 80
15. In a labeling machine, the combination, with means for pasting and delivering a label, a pusher mechanism for advancing the label-receiving article between the wipers, and a pair of flexible wipers supported at one edge; of a pair of yielding resistance-followers for upholding the flexible portion of said wipers, and a plurality of springs for effecting retro-action of the followers, said springs being arranged to progressively come into action for augmenting the resistance as the space between followers is increased. 85
16. In a labeling-machine, a pair of upright wiper-stands united at their feet, a pair of oppositely-swinging arms pivotally connected with said stands and having at their upper ends parallel follower-fingers, a spring or springs acting to press said follower-arms toward each other, means for insuring uniform movement of said follower-arms, and inwardly-projecting flexible wiper-flaps having their outer edges respectively secured to said wiper-stands, and their flexible ends resting upon said followers. 90
17. In a labeling-machine, in combination with means for pasting and delivering a label, wiping-on devices, and a pusher-head having means for conducting the bottle or article through the passway between said wiping-on devices; of a label-centering grip comprising rotatable grip-roller, means for supporting said roller carried on the pusher-head, and means for pressing said roll against the label and bottle oppositely to the bottle-pushing device. 95
18. In a labeling-machine, in combination with means for pasting and delivering a label, flexible wiper-flaps, laterally-movable followers beneath said wipers, and a reciprocating pusher-head having means for conducting a bottle through said wipers; of a label-center grip comprising a rotatable elastic roller mounted on a transverse axis in a vertically-swinging arm hinged to a support connected with the pusher-head, a spring acting to elevate the free end of said arm, and a projection or finger carried on said arm and adapted to engage beneath the wiper or wiper-follower, for the purpose set forth. 100
19. The combination of a pair of wiping-on devices, means for pasting and delivering a label adjacent to said wipers, a sliding pusher-head, guide-rods therefor, a bottle-pushing brace secured to said pusher-head, a label-gripping means provided with a yielding grip-roller disposed as a jaw in opposite relation to said pushing-brace, a support for said label-gripping means moving with the pusher-head, and a connecting-link jointing said pusher-head with the actuator means which works the label-delivering appliances. 105
20. In a labeling-machine, the combination, with the supporting-frame, oscillating carrier having pasting-pickers, swinging carrier-supports, bottle-pusher head, the actuator-lever and connection-links for moving said carrier and pusher-head; of the rocker-lever fulcrumed on the frame-base, the revolute cam engaging one arm of said rocker-lever, the rod connecting the other arm with said actuator-lever, a drive-pulley and an automatic stop-clutch for the cam, and a clutch-controlling lever pivoted on the base and provided with a toe-treadle and a reacting spring, substantially as set forth. 110
21. In a labeling-machine, for the purpose set forth, a label-holder having rearward and forward reciprocative action from a predetermined position at its front limit, and provided with label-supporting guide devices thereon, those for the rear edge of the labels being adjustably mounted upon the holder-plate and provided with means overhanging the edge of the label-pack; in combination with paste-applying pickers that reciprocatively move into conjunction with said holder for taking labels therefrom. 115
22. In a labeling-machine, the combination, with the pasting-pickers, the label-holder plate provided with upright label-supporting guards perpendicular to the plane of said plate, and means for moving the pickers onto 120

and from the top of a pile of labels seated upon said plate; of a finger device carried upon the holder-plate and projecting over the top of the labels resting thereon, said finger device being arranged for automatic or self-adjustment to conform to the decreasing height of the pile of labels above the plate, and adapted for lateral displacement to facilitate recharging the holder with labels.

- 10 23. In a labeling-machine, the combination with means for pasting and delivering the labels, wiping devices, and a pusher having means for passing a bottle through the wiping devices; of a label-center grip consisting of a freely-rotatable grip-roll, a movable spring-pressed arm carried upon the pusher and having the grip-roll axle mounted thereon, a spring for normally pressing said arm toward the bottle, and means for arresting 20 the approach movement of said arm and grip-roll when adjacent to, but before it reaches the primal position of the delivered label, for the purpose set forth.
24. In a labeling-machine, in combination 25 with means for pasting, placing and wiping on labels, a transferring-carrier carrying paste-applying pickers, a reciprocating bed mov-

able backward and forward in line with said carrier, a vertically-movable label-holder stand yieldably supported on said bed, a detachable label-holder plate mounted on said stand, label-holding guide devices thereon adjustable in relation to the axis of the stand, means for elevating said label-holder stand in relation to the bed, and means for reciprocating said bed and parts supported thereon, synchronous with the action of the transferring-carrier.

25. In a labeling-machine, in combination, with a reciprocating means for pasting and delivering labels; a vertically-movable label-holder carried upon a horizontally-movable bed, and means for moving said bed and label-holder to bring the latter into the path of said pasting and delivering means, and to 45 travel in unison therewith while taking a label from said holder.

Witness my hand this 25th day of June, 1902.

FRANK O. WOODLAND.
